UNITED STATES PATENT OFFICE.

ISAK OLAF TORKELSON, OF NEW BRIGHTON, NEW YORK.

PROTECTIVE DEVICE FOR CHISELERS.

1,370,933.

Specification of Letters Patent.

Patented Mar. 8, 1921.

Application filed April 23, 1920. Serial No. 376,160.

To all whom it may concern:

Be it known that I, ISAK OLAF TORKELSON, a citizen of the United States, residing at 234 Westervelt avenue, New Brighton, 5 in the county of Richmond and State of New York, have invented certain new and useful Improvements in Protective Devices for Chiselers, of which the following is a specification.

10 This invention relates to protective devices and in particular to a shield adapted for the use of chiselers, and it has for its main object to provide a device which may be readily attached to the hand, and which 15 restrains the movement of the chips flying from the point of the chisel, and prevents the same from reaching the eyes or limbs of the operator. Much annoyance is caused to chiselers by flying chips which often strike 20 the eye, and my device eliminates this injurious action by providing a screen located around the chisel point which shield is struck by the flying chips and which deflects them back toward the material operated 25 upon.

Another object of the invention is to provide such a protective device of simple and improved construction, which is both readily adaptable for use and inexpensive in cost 30 of manufacture.

The above and other objects of my invention will become apparent in the description below, in which like characters of reference refer to like-named parts in the drawings 35 which are illustrative of one embodiment of the invention and which form a part of this specification.

Referring briefly to the drawings,

Figure 1 represents my device in use, in 40 perspective projection; Fig. 2 is a sectional view taken substantially on the line A—A of Fig. 1;

Fig. 3 is a plan view of the locking means for retaining the transparent medium of 45 Fig. 1 in position; and

Figs. 4 and 5 are respectively front and side elevations of another screen constructed according to my invention.

Referring now specifically to the drawings, the numeral 1 denotes a chisel which 50 is grasped in the hand of the operator. A strap 3 is wound around the hand 2 and is adjustably locked by a buckle or hasp 8 of any desired construction. To the strap 55 3, I attach a screen member having a transparent portion which screen and attach-

ment means therefor may be of varied construction. In one example, a cage or frame 4 may be secured to the lower part 3' of the strap—as by stitches 13—in which frame is 60 a screen 5 which is preferably made of wire fabric or of other open-work material, although it may be of solid construction if desired. A window 7 may be located in the screen and retained by a frame 9, which 65 window may be made of glass, celluloid, isinglass, mica or other transparent material.

The frame 9 may be secured to the screen 5 by spring clips 10. Said frame may comprise an outer circular concave member or 70 grooved flange, the upper edges of which are folded over at 12 about said transparent material. The ring 11 is then fitted in said concave member or groove thereby retaining the said transparent medium therein and 75 under the edges 12.

If desired, the screen may comprise a cage or frame 4' having orifices 4" by which it may be attached to the lower part 3' of the strap 3 by fastening devices passing 80 through the perforations 6 indicated in dotted lines in Fig. 1. In the frame may be inserted a transparent plate 7' of glass, celluloid, isinglass, mica or other rigid or flexible material and a screen 5' preferably 85 of wire fabric or other protective material. It is manifest that if the screen mesh is made so as to be readily looked through, it may itself constitute the transparent medium.

Obviously the shield may be enlarged at 90 the lower part thereof. The said screen—comprising a transparent structure and protective means therefor—may have attachment means by which it may be attached to the part 3' at both the top and bottom 95 portions thereof as shown in Fig. 1, or at only the upper part of the same as indicated in Fig. 4.

In operation, the chips from the end of the chisel 1 strike the inner face of the shield 100 comprising the frame 4 and screen 5, and are deflected backward, thus preventing them from escaping and causing annoyance to the operator and others standing by.

I wish it to be understood that I do not 105 desire to be limited to the particular use or the exact details of construction shown and described, for obvious modifications will occur to persons skilled in the art.

What I claim as my invention is:—

1. A device of the class described comprising a strap exterior of and adapted to

- inclose the hand while grasping the body of a chisel, the strap being enlarged at the back of the hand and opposite the said chisel body; a semi-transparent protective 5 metallic shield carried by the said enlargement, and a transparent medium located in the shield opposite to the point of the chisel to form a window whereby the operation of the latter may be directed, the strap serving, 10 when desired, to prevent relative movement of the chisel with respect to the hand during the said operation and also to allow relative adjustment of the chisel at will.
2. A device of the class described comprising a strap exterior of and adapted to 15 inclose the hand while grasping the body of a chisel, the strap being enlarged at the back of the hand and opposite the said chisel body; a screen comprising a frame 20 and inclosed semi-transparent protecting metallic shield carried by the said enlargement, and a transparent medium located in the shield opposite to the point of the chisel to form a window whereby the operation 25 of the latter may be directed, the strap serving, when desired, to prevent relative

movement of the chisel with respect to the hand during the said operation and also to allow relative adjustment of the chisel at will.

3. A device of the class described comprising a strap exterior of and adapted to inclose the hand while grasping the body of a chisel, the strap being enlarged at the back of the hand and opposite the said chisel 30 body, a screen comprising a frame and inclosed semi-transparent protecting metallic shield carried by the said enlargement and another frame and a transparent medium therein, the latter frame being located in the 35 shield opposite to the point of the chisel to form a window whereby the operation of the latter may be observed and directed, the strap serving, when desired, to prevent relative movement of the chisel with respect to the hand during the said operation and 40 also to allow relative adjustment of the chisel at will.

In testimony whereof I affix my signature.

ISAK OLAF TORKELSON.
